DESIGN FOR A BICYCLE

Otto A. Trnka, Saugerties, N. Y.

Application June 10, 1946, Serial No. 130,575

Term of patent 14 years

(Cl. D90—8)

To all whom it may concern:

Be it known that I, Otto A. Trnka, a citizen of the United States, residing at Saugerties, in the county of Ulster and State of New York, have invented a new, original, and ornamental Design for a Bicycle, of which the following is a specification, reference being had to the accompanying drawing, forming a part thereof.

In the drawing:

Fig. 1 is a side elevational view of a bicycle, showing my new design;

Fig. 2 is a top plan view; and

Fig. 3 is a front elevational view of the same.

I claim:

The ornamental design for a bicycle, as shown.

OTTO A. TRNKA.
